UNITED STATES PATENT OFFICE.

JAMES REYNOLDS, OF NEW YORK, N. Y.

REAR SIGNAL.

1,201,762.

Specification of Letters Patent. Patented Oct. 17, 1916.

Application filed June 23, 1915. Serial No. 35,968.

To all whom it may concern:

Be it known that I, JAMES REYNOLDS, a citizen of the United States, and a resident of the city of New York, borough of Brooklyn, in the county of Kings and State of New York, have invented, a new and Improved Rear Signal, of which the following is a full, clear, and exact description.

My invention relates to rear signals for vehicles; and the object thereof is to provide a simple, inexpensive and efficient rear signal whereby the visual and hearing faculties of the person controlling a vehicle in the rear can be easily attracted.

With the above and other objects in view, the nature of which will more fully appear as the description proceeds, the invention consists in the novel construction, combination and arrangement of parts as herein fully described, illustrated and claimed.

In the accompanying drawings, forming part of the application, similar characters of reference indicate corresponding parts in all the views.

Figure 1 is a side elevation of my rear signal and the mechanism for operating the same; Fig. 2 is a vertical section on line 2—2, Fig. 3; Fig. 3 is a front elevation of the rear signal; Fig. 4 is an enlarged section through the bearing for the rear signal; Fig. 5 is an end elevation of the drum, including the bearing for returning the signal to its original position; and Fig. 6 is an elevation of the drum from the opposite end showing the pawls whereby the drum is connected or disconnected from the transmission means.

Referring to the drawings, 7 represents a lamp housing forming a reflector and which is rigidly secured to a tubular member 8 projecting from a bracket 9. Secured to the tubular member within the reflector is an incandescent lamp 7' the conduits for which pass through the tubular member. The housing has a glass-screened side opening 8' to direct light from the lamp 7' on to the license number. By means of the bracket the signal is secured to any desired place in the rear of a vehicle. Mounted on the tubular member 8 between the housing 7 and the bracket 9 is a ball bearing 10, cones 11 of which being adjustably mounted on the tubular member 8. The revolvable part of the bearing has a circular flange 12 to one side of which a pinion 13 is rigidly attached. Secured to the other face of the flange 12

are arms 14 which are arcuated to conform with the curvature of the housing 7, and which arms extend from the flange to the front of the housing.

Secured to the housing at the front thereof is an outer circular raceway 15 the balls 16 of which are maintained in position by a sectional ring 17 which encompasses the raceway 15. Each of the sections of the ring 17 has an ear 18 secured to the corresponding arm 14, so that the ends of the arms 14 are made to bear on the housing 7. One of the sections of the ring has beveled joints 19 whereby wear in the ball bearing formed by the raceway 15 and the sectional ring can be taken up.

Secured to the end of the arms 14 adjacent the sectional ring 17 is a housing front 20 which has a plurality of sectorial openings 21, each of the openings 21 having a transparent member. The alternate transparent members are of different colors, and as shown in the drawings, the transparent members 22 are colorless, while the transparent members 23 are red. Of course, if desired, any other color may be used. Secured to the periphery of the housing front 20 are whistles 24 which become operative when the pinion 13 is rotated.

Meshing with the pinion 13 is a gear 25 which has a ratchet 26 rigid and concentric therewith, the pinion having a shaft 27 connected thereto and bearing in the bracket 9. Mounted to turn on the shaft 27 is a drum or reel 28, the end of the reel adjacent the gear being recessed and provided with gravitationally operable pawls 29 adapted to engage the ratchet 26 when said drum is rotated in a predetermined direction. The other end of the drum is recessed and therein a spring 30, preferably such as a clock spring, is provided, one end of the spring being secured to the shaft 27 and the other end to the drum. The said spring is adapted to be wound when a pull is exerted on the flexible member 31 wound on the reel so as to unwind the same. The pull on the flexible member may be produced by any suitable means located at the seat of the driver.

The operation of my device is as follows: If a driver of a car wishes to change the course of the car, he pulls on the flexible member 31. This will cause a swift revolution of the drum or reel and therewith the gear 25, due to the engagement of the pawls 29 with the ratchet 26. The revolution of

the gear will set the pinion 13 into revolution and therewith the arms 14 and the front of the lamp housing connected thereto. The revolution of the reel winds the spring 30, the unwinding of which restores the drum 28 to its normal position without revolving the gear 25, due to the fact that there will be no binding engagement between the ratchet and the pawls. The revolution of the housing front will render the whistles operative and attract attention of the hearing faculties of the car drivers that are behind and indicate that a car is intending to change its course. The revolution of the colored sectors will indicate the car intending to change its course. The noise of the whistle is the attraction; thus notifying the drivers near by so that they may avoid collision. If the car driver wishes to turn out to pass a car in front of him, two operations, that is, two pulls on the reel will indicate this intention, and the revolving of the lamp front, as stated, will designate the car that is to be turned. If a car driver wishes to turn around, that is, to go in the opposite direction from where he was going, he may operate three times, that is, pull three times on the flexible member 31. It will be noticed that in all cases the noise produced by the whistles attracts the attention, while the revolution of the multi-colored housing front indicates which of the cars is to change its course. In lieu of the code of signals described, any other may be selected.

35 While I have described the principle of operation, together with the device which I now consider to be the best embodiment thereof; I desire to have it understood that the device shown is merely illustrative and 40 that such changes may be made as are within the scope of the appended claims.

I claim:

1. In a vehicle rear signal, a lamp housing, a revoluble housing-front, whistles carried by the front and becoming operative when the front is revolved, and means for revolving the front.
2. In a vehicle rear signal, a lamp housing, a revoluble housing-front having differently colored transparent sectors, whistles carried by the front and adapted to become operative when the front is revolved, and means for revolving the front operable from the place from where the vehicle is controlled.
3. In a vehicle rear signal, a bracket, a lamp housing secured to said bracket, a lamp-housing front mounted to revolve on

the housing, a member mounted to rotate on the bracket and connected to the front, 60 means for rotating said member positioned on the bracket and operable from the place from where the vehicle is controlled, and whistles carried by the housing front and becoming operative when said front is rotated.

4. In a vehicle rear signal, a bracket having a tubular extension, a lamp housing secured to said tubular extension, a lamp within the housing secured to the tubular extension, a housing front mounted to revolve on the housing, whistles associated with the front and becoming operative when the front is revolved, a pinion mounted to revolve on the extension, means connecting the pinion 75 to the front, a gear in the bracket meshing with the pinion, a drum free to revolve relative to the gear, means for binding the drum to the gear when the same is revolved in a predetermined direction and whereby the 80 front is revolved, a flexible member on the drum, the unwinding of which causes the revolution of the drum, and a resilient member for restoring the drum to its normal position whereby the flexible member is 85 wound on the drum.

5. In a vehicle rear signal, a bracket, a lamp housing secured thereto, a multi-colored transparent housing front mounted to revolve on the lamp housing, whistles secured to the housing front and becoming operative when the housing is revolved, a driven member in said bracket, a pinion coaxial with the housing, arms connecting the pinion to the front, and means for driving 95 the pinion located in the bracket and operable from the place from where the vehicle is controlled.

6. In a vehicle rear signal, a bracket, a lamp housing secured thereto, a housing front mounted to revolve on the housing, whistles carried by the front and becoming operative when the front is revolved, a transmission from the drum to the front, a flexible member normally wound on the drum, means 100 for locking the drum to the transmission when the flexible member is unwound, and a resilient member for rewinding the flexible member.

In testimony whereof I have signed my 110 name to this specification in the presence of two subscribing witnesses.

JAMES REYNOLDS.
